UNITED STATES PATENT OFFICE.

RICHARD MARX, OF PHILADELPHIA, PENNSYLVANIA, ASSIGNOR TO DEFIANCE MANUFACTURING COMPANY, OF PHILADELPHIA, PENNSYLVANIA, A CORPORATION OF PENNSYLVANIA.

CORN-RAZOR.

1,239,419.

Specification of Letters Patent.

Patented Sept. 4, 1917.

Application filed December 5, 1914. Serial No. 875,607.

To all whom it may concern:

Be it known that I, RICHARD MARX, a citizen of the United States, residing in Philadelphia, Pennsylvania, have invented 5 certain Improvements in Corn-Razors, of which the following is a specification.

One object of my invention is to provide a razor particularly adapted for cutting or trimming hardened skin growths such as 10 corns or calli, which shall have its parts so arranged as to permit full view of the part being operated on, while embodying the advantageous features of a safety razor, as regards the impossibility of making objectionably deep cuts.

It is further desired to provide a simple, substantial and inexpensive form of safety corn razor of such design that it is convenient to use, that it cuts with an inclined 20 or drawing stroke, and has its parts so arranged and proportioned as to clear itself of the material cut.

These objects and other advantageous ends 25 I secure as hereinafter set forth, reference being had to the accompanying drawings in which,

Figure 1 is a plan of a corn razor constructed according to my invention;

Fig. 2 is a side elevation;

Fig. 3 is an inverted plan of the holder or main portion of the device;

Fig. 4 is a plan of the blade;

Figs. 5 and 6 are respectively an inverted plan and a perspective view of the cover 35 plate;

Fig. 7 is an enlarged section on the line $a-a$, Fig. 1, and

Fig. 8 is a transverse section, likewise on an enlarged scale, on the line $b-b$, Fig. 1.

40 In the above drawings, 1 represents the body or frame of the razor which is preferably formed of a single stamping of sheet metal, including a handle portion 2, and a body portion 3 whose outer or free end is

45 downwardly flanged to provide a shoulder 4. It is to be noted that this shoulder extends in a straight line at an acute angle to the general line of said body portion which, immediately at its ends adjacent said flange

50 has two ears 5, lying substantially in its plane. In the body portion 3 are formed two openings 6 and 7 defining a relatively narrow crossbar 8 extending parallel to the line of the flange 4, and as shown in Fig. 7,

having its edge adjacent the opening 6 undercut or beveled from the top surface downwardly. The handle portion 2 extends upwardly from the general plane of the body portion 3 at an angle of about 30 degrees, and said body portion is preferably so formed as to be concave underneath and convex on its top surface.

The razor blade 9 is rhomboidal in outline and at the rear ends of its two sides has two projecting lugs 11 so formed as to register with the ears 5 of the body 3 when the blade is laid in position thereon, it being noted that said body, rearwardly from the cross bar 8 has the general outline of the blade. The latter, when mounted in position upon the body of the holder, contacts with the same along a line immediately adjacent the flange and at two points 12 adjacent the ends of the cross-bar 8, whose main portion, however, is elevated above the plane of the cutting edge 10 as shown in Fig. 8. This blade is held in place by a cover plate 13, which like the blade, is rhomboidal in outline and has its forward edge beveled or thinned. Its ends are provided with a pair of integral clips 14 which, when it is mounted upon the blade, extend upwardly around the edges of the same, with their turned-over ends in engagement with the top convex surface of the body 3 as shown in Fig. 7.

When so mounted the forward beveled edge of the cover plate extends across the holder to the rear of the cutting edge of the blade which is parallel with and slightly to the rear of the forward edge of the cross-bar 8. The design of the clips 14 is such that when the cover plate is forced back as far as possible, their rear edges strike the lugs 11 of the blade forcing its rear edge tightly against the flange 4, while their overhung portions frictionally engage the convex upper surface of the body 3 so as to effectually hold the cover plate and blade from dislodgment.

Under conditions of use, when the parts are assembled as shown in Figs. 1 and 7, it is obvious that anything operated on, such as a corn, is visible through the opening 7 in the body of the frame or handle structure so that the person using the instrument may see precisely what is being engaged by the cutting edge.

this purpose the sheave case 4, as in Figs. 2 and 3, may be provided with ears bent to form eyes 7 which engage a reinforcement member in the form of a rod that may comprise a U-shaped portion 8 extending from the eyes 7 to near the bottom end of the weight block 1 and that may also comprise outwardly and downwardly bent terminal portions 9 forming hooks to retain the case 4 against upward movement.

The sheave case 4 may be provided with a flange 10 which in Fig. 2 is embedded in the block 1 so that its outer face is flush with the upper end of said block.

15 The lower end of the block 1 may be provided with a notch or groove 11 extending transversely to the U-shaped portion 8 of the reinforcement rod, the top of the groove being above the level of the lower portion of 20 the U-shaped member so that a portion 12 of the U-shaped member will extend through the groove 11 transversely thereof in order that a hook, not shown, of a supplemental weight block, not shown, may be hooked over 25 the portion 12 to increase the weight for balancing the sash or sashes with which the block 1 is to be connected.

In practice the weight block 1 will be inserted in the chamber adapted to contain it 30 and one end of the sash cord, not shown, previously fastened to one sash will be forced through the space between the sheave 3 and case 4 and said end will be fastened to the other window sash in the usual manner so that the block 1 will be suspended and will act as a counterbalance to the window sash, or window sashes in case two sashes are connected to the one weight as is often the case.

40 From the foregoing it is clear that the sash cord may be readily threaded around the sheave 3 and that practically the entire space above the block 1 is free from anything that would interfere with the block 45 being drawn close to the pulley in the window frame as is readily understood, this being due to the fact that the sheave 3 is mounted in the recess 2. An important feature of this invention is the curved guide or 50 track *a* for facilitating the threading of the sash cord to the weight, and it is obvious that either iron or cementitious material could be employed for the construction of the block 1. It is of course preferable, 55 cause of less cost, to employ the cementitious material, but in the case of extraordinarily large windows it may be advisable at times

to employ iron or other metal in the manufacture of the block 1.

In the manufacture of the improved sash weight, shown in Figs. 2 and 3, the sheave 3 and the parts for mounting said sheave will be placed in a suitable mold, not shown, and the material of which the block is to be formed, will then be poured or placed in 65 the mold so that the sheave will be cast in place as is readily understood.

From the foregoing it is clear that I have provided a recess with a semicircular track and that a sheave is journaled in the recess 70 and spaced from the semicircular track so that when the end of a sash cord is pushed into the recess along the curved track it will readily pass along the periphery of the sheave, first downward then beneath and 75 finally upward so that said end may be readily grasped by the workman as said end issues from the recess. It is readily seen that the sheave 3 and its case 4 can be inserted in the recess 2 through the mouth of said recess 80 because said mouth is unobstructed.

I claim:

1. A sash weight comprising a concrete block having a recess in one end, a reinforcement rod embedded in said block, and 85 a sheave in the recess anchored to said reinforcement rod.

2. A sash weight comprising a concrete block having a recess in one end, a sheave case in said recess, a sheave rotatively 90 mounted in said sheave case, said sheave case being curved to conform peripherally with the sheave, and a reinforcement rod embedded in the block and connected with said sheave case.

3. A sash weight comprising a sheave case having a hollow shaft, a sheave journaled on said shaft, and a block embracing the sides of said sheave case and forming a core inside of said hollow shaft to anchor the 100 sheave case.

4. A sash weight comprising a block having a recess in one end, a sheave case in the recess having eyes, a sheave rotatively mounted in said sheave case, and a reinforcement rod embedded in the block and forming hooks engaging said eyes.

Signed at Los Angeles, California, this 20th day of February, 1917.

CHARLES L. MARTIN.
